UNITED STATES PATENT OFFICE

WILLIAM L. COOPER AND LEON D. FORTIER, OF KANKAKEE, ILLINOIS, ASSIGNEES TO SEARS, ROEBUCK AND CO., OF CHICAGO, ILLINOIS, A CORPORATION OF NEW YORK

LIQUID-FUEL STOVE

Application filed August 4, 1927. Serial No. 210,513.

The invention relates to liquid-fuel stoves and particularly to stoves in which combustion of the fuel is effected by means of the so-called wickless type of oil burner.

Ordinarily, the wickless type of oil burner comprises a bowl having a relatively deep annular channel therein arranged to contain a supply of fuel for immediate combustion. The height of the flame produced by the burner is regulated by varying the amount of fuel in the annular channel and this is generally accomplished by raising or lowering the burner bowl with reference to a constant level supply source of the fuel, the source and the bowl being, of course, suitably connected. The ultimate aim of the invention is to provide an improved mechanism applied, in this instance, directly to the burner to effect a raising or lowering of the fuel level therein.

In prior devices of this character it has been customary to control the raising and lowering of the burner by means of a rotatable operating member which had the disadvantageous feature of requiring a considerable rotational movement to move the burner from an "off" to an "on" position or reverse.

The primary object of the invention is to provide a new and improved rotatable means for adjusting a burner, which is readily and conveniently operable to vary the position of the burner and which effects such an adjustment by means arranged to increase the movement of the operating member to such an extent that a relatively small movement of the member produces a relatively large raising or lowering of the burner.

A particular object of the invention is to provide an operating means including a shifting cam member which produces a multiplied movement of the burner.

Another object is to provide a cam member which is so arranged as to permit ready disassembly for cleaning, repairs, replacement of parts and like reasons.

Other objects and advantages will become apparent in the following description of an exemplary form of the invention and from the accompanying drawings, in which:

Figure 1 illustrates a view in elevation of

a portion of a stove embodying a wickless oil burner with a part thereof removed as shown by the section line 1—1 of Fig. 2.

Fig. 2 is a sectional view of the invention taken on the line 2—2 of Fig. 3.

Figs. 3 and 4 are rear views of the device showing the raised and lowered positions of the burner.

Although the invention is susceptible of various modifications and alternative constructions, we have shown and herein described in detail the preferred embodiment but it is to be understood that we do not thereby intend to limit the invention to the specific form disclosed but intend to cover all modifications and alternative constructions falling within the spirit and scope of the invention as expressed in the appended claims.

In the drawings, one of the usual groups of burners has been shown as being mounted for independent movement vertically with respect to a fixed constant level fuel supply (not shown). The burner bowl 5 in this instance comprises the part which is raised and lowered and provides the usual annular channel 6. A suitable mounting for the bowl in the form of the supporting member 7 is vertically adjustable relative to the stove body, a portion of the frame of which is shown as the front plate 8. A fuel supply pipe 9 which preferably is common to all of the burners carries an oil riser 10 suitably connected, as by welding, to the pipe to provide a leak proof joint.

A fuel pipe 11 is rigidly carried by the burner bowl 5 and is arranged to telescope into the riser 10 through an appropriate stuffing box 12. Other suitable means of providing an extensible connection between the riser and the bowl may be provided but the telescoping arrangement is preferred since a certain measure of support is afforded the bowl thereby.

Extending rearwardly from the front plate 8 is a rigid bracket 13 (Fig. 2) which comprises a plate 13^a perpendicularly disposed relative to the front plate 8, a pair of laterally spaced front and rear members 14, 15, and a pair of vertically spaced horizon-

tal arms 16. The bracket in this embodiment is suitably secured through the front member 14 to the front plate 8 of the stove as by means of the bolts 17. The oil riser 10 extends through the vertically spaced arms 16 and is secured thereto by such means as the lock nuts 18 thereby producing a rigid assembly.

In attaining the objects of the invention, means has been provided in the present instance which produces the desired vertical movement of the bowl, which means also is adapted to resist any accidental displacement or unintended movement of the bowl. The means comprises herein a cam member rotatable in either direction at the option of an operator which cam member is operatively associated with the burner to produce the raising or lowering thereof. In addition the cam member is arranged to be moved vertically relatively to the stove and independently of the burner to produce a more rapid movement of the burner.

To this end, there is provided in the front plate 8 of the stove and in the spaced members 14, 15 of the bracket a series of aligned vertical slots 19 through which the shaft 20 of an operating member extends. Normally the shaft 20 rests upon and is supported by the lower edges of the slots 19 and sufficient clearance between the sides of the slots and the shaft permits free vertical movement thereof through the length of the slots. The inner end of the shaft 20 carries a cam member in the form of a disk 21 which is provided with a spiral or scroll cam slot 22, the arrangement of parts being such that the surface of the cam is spaced only a small distance from and parallel to the surface of the inner member 15. Since the scroll cam slot 22 is of considerable length means may be provided to reinforce the cam disk 21, which means in this instance comprises a diametrically positioned stay 23, having raised portions 24 thereon over each intersection with the slot 22 to permit the cam followers, hereinafter described, to pass readily therebeneath.

The increase or multiplication of the movement of the operating member in adjusting the burner bowl vertically is effected by the association of a pair of cam followers with the cam slot by which the burner bowl 5 and its support 7 are moved relatively with respect to the cam 21 and the cam at the same time is moved relatively with respect to the stove.

To this end a cam follower in the form of a pin 25 is rigidly secured near the lower end of the burner bowl support 7. A second pin or follower 26 is securely mounted on the upper portion of the inner bracket member 15 and projects outwardly therefrom. When the parts are in assembled relation the burner bowl support 7 is positioned for sliding

movement intermediate the cam disk 21 and the bracket 13. The support is provided with a vertical slot 27 through which the cam follower 26 secured to the bracket 13 extends to engage one part of the cam slot 22. The cam follower 25 on the support 7 is arranged to engage the cam slot at a point below and in vertical alignment with the follower 26. By this arrangement it will be seen that when the cam disk is rotated the engagement of the stationary follower 26 on the bracket with the cam slot 22 causes the cam disk to move vertically in one direction or the other with the operating shaft 20 riding upwardly or downwardly in the aligned slots 19 in the bracket and the front plate. At the same time the engagement of the other cam follower 25 with the slot 22 will effect a corresponding raising or lowering movement of the support 7 and burner bowl 5 with respect to the cam disk 21. Consequently, the action of the cam in moving through a given angular distance results in a vertical movement of the burner bowl through a distance approximately double the distance which could be attained in the customary manner. Thus it is possible to provide a burner in which, at the most, a single revolution of the operating member causes a movement of the burner bowl from its upper to its lower limit or vice versa.

As shown in Fig. 2, the operating shaft 20 extends forwardly beyond the front plate 8 a convenient distance and is squared at the end as at 28 to receive a suitable handle 29. A tubular sleeve 30 fits loosely about the shaft 20 intermediate the handle and the bracket and bears against a washer 31 which extends across or straddles the slot 19 in the bracket member 14. The parts are secured together in operating relation by suitable means such as the nut 32 screw threaded on the end of the shaft.

Since in this embodiment, it is possible to completely raise or lower the burner by less than one revolution of the operating member, indicating means to aid in determining the position of the burner with respect to the constant level fuel supply may be provided directly upon the front or face plate and the operating member. In the present instance this means comprises suitable indicia or indicating characters 33 painted, stamped or otherwise positioned upon the face plate about the operating shaft. The shaft carries an indicating means herein shown in the form of a head 34 having a squared aperture therein to fit the squared portion 28 of the shaft and a pointer 35 positioned adjacent the face plate 8 by means of an offset portion 36 of the indicator therebetween.

By the construction provided it is only necessary to unscrew the nut 32 to permit the handle 29, the indicator 34, the sleeve 30 and the washer 31 to be removed from the

shaft 20. The cam disk 21 and the shaft may then be withdrawn from the bracket 13, which permits the burner bowl 5 to be withdrawn from its engagement with the bracket. Thus, the entire device may be readily assembled or may be taken apart for cleaning, repair or any other cause by simply removing the single securing means.

From the detailed description of the preferred embodiment of the invention, it will be apparent that a burner regulating mechanism has been provided in which only a relatively small movement of an operating member is necessary to effect a movement of the burner through its entire range of travel; which, moreover, is simple in construction and which may be quickly and easily taken apart and assembled.

We claim as our invention:

1. A liquid fuel stove comprising, in combination, a stove body, a wickless fuel burner including a burner bowl, a vertical fuel supply pipe, a pipe connected to and carried by said bowl and telescoping with the vertical supply pipe, a bracket secured to the stove body, said bracket and body having vertical elongated aligned slots therein, an operating shaft extending through said slots in said body and bracket and capable of vertical movement in said slots, a cam carried by the inner end of said shaft adjacent the inner side of said bracket, said cam having a scroll cam slot therein, a support for said bowl positioned for vertical movement between the bracket and the cam, a cam follower fixed to said bracket, and a second cam follower carried by said movable support, said pins being arranged to engage said cam slot at spaced points thereon whereby rotational movement of said operating shaft effects a vertical movement of said shaft and cam and a more rapid vertical movement of said support and bowl.

2. A liquid fuel stove comprising, in combination, a stove body, a burner bowl for a wickless fuel burner, means establishing communication between said bowl and a fuel supply of substantially constant level, a vertically movable support for said bowl, a cam having a scroll cam slot therein adjacent a part of said movable support and movable vertically a limited distance, means for rotating said cam, means fixed on said stove body and engaging said cam slot to effect a vertical movement of said cam when said cam is rotated, and means on said movable support associated with said cam slot to effect a simultaneous vertical movement of said support.

3. A liquid fuel stove comprising, in combination, a stove body, a burner bowl for a liquid fuel stove, a vertically movable support for said bowl, and manually operable means for raising or lowering said bowl, said means including a cam associated with

a fixed part of said stove body to effect a raising or lowering movement of said cam upon rotation thereof, and means upon said movable support associated with said cam for effecting a simultaneous raising or lowering of said support relative to said cam.

4. In a liquid fuel stove, in combination, a stove body, a burner bowl, a vertically movable support for said bowl, a scroll cam mounted on said stove body arranged for limited vertical movement relative to said stove body upon rotation of the cam, and means on said support engaging said cam to effect a vertical movement of said burner bowl relative to said cam.

5. In a wickless fuel burner, in combination, a frame, a fuel container adapted to be positioned to change the fuel level therein to regulate a flame, a support for said container adapted for vertical movement relative to the frame, and means mounted on said frame for adjusting the position of said container, said means being movable vertically relative to said frame and adapted simultaneously with the movement thereof to effect a vertical movement of said support relative to said means whereby the change in position of said container may be effected by a limited movement of said means.

6. The combination with a fuel receptacle mounted for up and down movement, of raising and lowering means for the receptacle including a scroll cam adapted to move upwardly or downwardly upon rotation thereof said receptacle being connected to said cam for up-and-down movement relative thereto as said cam is rotated whereby operative rotation of said cam effects a multiplied movement of said receptacle.

7. In a burner regulating mechanism, a bracket, a shaft mounted in said bracket, a regulating member rigidly secured to one end of said shaft, an operating handle carried by the other end of said shaft, a sleeve mounted about said shaft intermediate said bracket and operating handle, and a single removable means on said other end of said shaft for securing the parts in assembled relation.

8. In a wickless fuel stove, in combination, a fuel container adapted to be moved vertically to effect a variation in the height of or to extinguish a flame therein, and operating means for moving said burner including a rotatable and vertically shifting cam member connected to said container and adapted to move said container vertically relative to said member in the shifting movement thereof.

9. The combination of a stove frame having guides, a burner, a supporting member for the burner, slidably vertically on the frame to raise or lower the burner, an operating handle and shaft rotatable and also movable vertically in the guides of the frame,

and means actuated by rotation of the handle and shaft to raise or lower the supporting member relative to the shaft and simultaneously raise or lower the shaft in said guides relative to the frame.

5 In testimony whereof we have hereunto affixed our signatures.
